(57) **CLAIM**

The ornamental design for a tissue dispenser, as shown and described.

DESCRIPTION

This application relates to the following design applications being filed concurrently herewith:

Application Ser. No. 29/350,301 entitled Towel Dispenser

Application Ser. No. 29/350,305 entitled Tissue Dispenser

Application Ser. No. 29/350,314 entitled Soap Dispenser

Application Ser. No. 29/350,312 entitled Air Freshener Dispenser

The disclosures of the foregoing applications are hereby incorporated into this application in their entirety by reference thereto.

FIG. 1 is a top, front, and right side perspective view of a tissue dispenser showing my new design;

FIG. 2 is a right side elevation view thereof, with the left side being a mirror image of that shown;

FIG. 3 is a front elevation view thereof;

FIG. 4 is a top plan view thereof;

FIG. 5 is a bottom plan view thereof; and,

FIG. 6 is a rear elevation view thereof.

The broken line disclosure is understood to represent portions of the article in which the claimed design is embodied, but which form no part of the claimed design.

1 Claim, 5 Drawing Sheets
